UNITED STATES PATENT OFFICE.

CLEON M. HANNAFORD, OF RICHMOND, VIRGINIA, ASSIGNOR TO CAR DEVICES COMPANY, OF RICHMOND, VIRGINIA, A CORPORATION OF VIRGINIA.

FRONT DRAFT LUG.

Application filed May 23, 1925. Serial No. 33,428.

This invention is in the nature of a modification of or an improvement upon the front draft lug forming the subject of the application of Arthur H. Weston; for patent for 5 front draft lugs, filed February 20, 1925, Serial No. 10,617 Patent Number 1,551,353, dated August 25, 1925.

The invention consists in the outside addition to the front draft lugs of reinforcing 10 members which flank the ribs and rearward extensions of the lugs of the Weston invention, these reinforcing members having bolt holes that receive six of the bolts or rivets used to secure the Weston front draft lugs 15 to the webs of the center sill members and four additional bolt holes to receive bolts or rivets flanking the sides of the rearward extensions, the heads of the four additional bolts or rivets being countersunk on the inner sides so as not to encroach upon the limited 20 space between the center sill members for the play of the draft gear mechanism, as I will proceed now to set forth and finally claim:

25 In the accompanying drawings illustrating the invention, in the several figures of which like parts are similarly designated, Figure 1 is a horizontal section, and Fig. 2 is a side elevation of sufficient of the draft 30 mechanism to show my invention. Fig. 3 is a perspective view of one of the reinforcing members detached.

Without thereby limiting the invention to any particular form of draft rigging or 35 draft sills or center sills, the invention will be described, by way of illustration, in connection with a center sill made up of two metal channel beams, set with their webs upright and in parallelism and spaced apart 40 sufficiently to admit the draft gear.

The channel beams, as shown in detail in Fig. 2, have the bottom flanges 1, top flanges 2, and webs 3, all of any usual or approved construction, and have their webs slotted longitudinally, as indicated at 4, to permit the ribs of the draft lugs, hereinafter particularly described, to extend through and beyond the said webs.

5 is the outer portion of an ordinary yoke, 50 6 is the shank of the coupler, 7 is the striking plate, and 8 is the draw-bar carrier, all of ordinary or approved construction.

The invention herein is not limited to these details, and is adaptable to other constructions.

The front draft lug of the Weston patent above mentioned, comprises a plate 9, having the side shown uppermost in Fig. 3 of that patent and as herein shown, as a substantially flat surface, but provided with the longitudinal ribs 10, parallel with an intermediate slot 11, and surrounding the inner end of said slot, so that the lug may be fitted flat and snug against the inside surface of the web of the center sill, with the ribs 60 65 extending through the slot 4, and said ribs projecting outside of the web. These ribs are extended at 12 beyond the end of the lug, and such extension enters the slot in the web, thereby serving to align the parts and transmit strains to the center sill. The lug is provided with the transverse projection 13 on the opposite or inner side, so as to form an abutment for the front follower 14. This projection or abutment 13 preferably is reinforced by the inclined ribs 15, and there are similar ribs 16 at the longitudinal edges of the lugs which extend back to and reinforce the abutment 13.

The plate 9 extends not only laterally beyond the slot and its ribs 10, but also extends forwardly at 17 so as to completely overlie the slot in the web of the center sill.

The front draft lug may be secured to the web of the center sill by any suitable 85 means, preferably rivets 18, applied through the series of holes 19.

The front draft lug may be conveniently made as a single unitary casting, and preferably of steel.

As already indicated, one of these lugs is secured to each of the center sill members on the inner side thereof, and when the coupler and yoke are placed in position between them, they are secured by means of any suitable transverse key 20, preferably headed at 90 95 21 on one end and provided with a hole 22 at the other end to receive a cotter-pin or other fastening means. The slots 11 in the lugs are made sufficiently large to allow for necessary motion of the draft gear, and so that in buffing the transverse key will abut against the extended surfaces of the lugs, the strain being taken off of the rivets practically by the solid or unslotted rearward extension 12.

As already sufficiently indicated, the front draft lug of the Weston invention is intended to take the place of the front draft lugs heretofore used, same being a component part of 110

all draft arrangements, inclusive of vertical plane yoke and friction draft gear.

As shown in Fig. 1, the rearward extensions 12 and the ribs 10 project outwardly from the slots in the webs of the center sill members.

In order to reinforce these lugs and ribs and their external projections, the present invention includes the U-shaped members 23 having the bolt or rivet holes 24, here shown as ten in number. These reinforcing members are applied to the webs of the center sill members on the outer sides thereof and in longitudinal alinement with the lugs and straddling the ribs 10, and six of the bolts or rivets 18 by which the lugs are secured, also pass through the reinforcing members, while four additional bolts or rivets 25 are used above and below the rearward extensions 12 for additional reinforcing purposes, and these four bolts or rivets 25 have their heads 26 countersunk in the webs of the center sill members as shown by dotted lines in Fig. 1, so as not to obstruct the play of the draft gear between the sill members.

These reinforcing members may be castings, or of wrought metal, or forgings.

As will be observed, the reinforcing members directly engage and seat against the rear portion 12 of the draft lugs and in this way provide additional strength at the intersection of the draft lugs and the center sill members.

The present invention in addition to its reinforcing of the structure, has all of the advantages of the construction shown in the Weston application.

Variations in the details of construction are permissible within the principle of the invention and the scope of the claims following.

What I claim is:—

1. A front draft lug, of the character described, having an outwardly projecting rear extension, and an externally applied reinforcing member directly engaging and seating against the rear extension.

2. A front draft lug, of the character described, provided with an outwardly projecting rear extension, and a U-shaped reinforcing member externally applied and secured to the lug and directly engaging and seating against the rear extension.

3. A front draft lug, of the character described, provided with an outwardly pro-

jecting rear extension, and a U-shaped reinforcing member externally applied and secured to the lug by the same fastening means used to attach the lug, said reinforcing member directly engaged and seating against the rear extension.

4. A front draft lug, of the character described, provided with an outwardly projecting rear extension, and a U-shaped reinforcing member externally applied and secured to the lug by the same fastening means used to attach the lug, and additional fastening means applied beyond the body of the lug, said reinforcing member directly engaging and seating against the rear extension.

5. The combination with center sill members, provided with longitudinal slots, of front draft lugs slotted longitudinally and provided with ribs flanking the sides and the inner ends of the slots in the lugs, said ribs extending solidly beyond the slots in the lugs, the ribs and the extensions fitted in the slots in the center sill members, and the lugs fixedly secured to the center sill members on the inner sides thereof, and reinforcing members applied to the webs of the center sill members on the outer sides thereof about the ribs of the lugs and directly engaging and seating against the rearward extensions and held in place by fastenings used to secure the lugs in place.

6. The combination with center sill members, provided with longitudinal slots, of front draft lugs slotted longitudinally and provided with ribs flanking the sides and the inner ends of the slots in the lugs, said ribs extending solidly beyond the slots in the lugs, the ribs and the extensions fitted in the slots in the center sill members and the lugs fixedly secured to the center sill members on the inner sides thereof, and reinforcing members applied to the webs of the center sill members on the outer sides thereof about the ribs of the lugs and directly engaging and seating against the rearward extensions and held in place by fastenings used to secure the lugs in place and having additional fastenings arranged above and below the rearward extensions of the lugs and engaging the webs of the center sill members.

In testimony whereof I have hereunto set my hand this 27th day of May A. D. 1925.

CLEON M. HANNAFORD.
